UNITED STATES PATENT OFFICE.

JOHN C. TELLER, OF MINNEAPOLIS, MINNESOTA, ASSIGNOR OF FORTY-NINE ONE-HUNDREDTHS TO ZARAH C. COLBORN, OF MINNEAPOLIS, MINNESOTA, AND WILLIAM T. COLBORN, OF KANSAS CITY, MISSOURI.

SUPPLEMENTAL DRAFT DEVICE FOR FURNACES.

No. 881,166.

Specification of Letters Patent. Patented March 10, 1908.

Application filed May 11, 1907. Serial No. 373,066.

To all whom it may concern:

Be it known that I, JOHN C. TELLER, a citizen of the United States, residing at Minneapolis, in the county of Hennepin and State 5 of Minnesota, have invented certain new and useful Improvements in Supplemental Draft Devices for Furnaces; and I do hereby declare the following to be a full, clear, and exact description of the invention, such as will 10 enable others skilled in the art to which it appertains to make and use the same.

My invention has for its object to provide a supplemental draft device for furnaces, and to this end it consists of the novel devices and 15 combinations of devices hereinafter described and defined in the claims.

The device is especially adapted for application to the door of a furnace, and when so applied, it affords means for introducing air 20 directly upon the burning products of combustion, and this serves to more complete combustion. Such a device, therefore, not only serves to abate the smoke nuisance, but effects a great saving in fuel.

25 The improved supplemental draft device in its preferred form is illustrated in the accompanying drawings, wherein like characters indicate like parts throughout the several views.

30 Referring to the drawings, Figure 1 is a view in elevation with some parts broken away, showing the improved draft device applied to the door of a furnace. Fig. 2 is a view of the parts shown in Fig. 1, partly in 35 plan and partly in horizontal section. Fig. 3 is a transverse vertical section taken on the line $x^3 x^3$ of Fig. 2; and Fig. 4 is a view in elevation with parts broken away, looking at the inner end or nozzle portion of the draft 40 device.

The numeral 1 indicates a furnace door which may be of the usual or any suitable construction, but is preferably mounted so that it may be moved to and from an open 45 position while held parallel to its seat on the door opening. To accomplish this, it is pivotally connected at its intermediate upper and lower portions to the prongs of a yoke 2, which in turn is hinged or pivotally 50 connected to the furnace by means of hinge bolts 3 passed through lugs 4 of said yoke and through lugs 5 on the furnace adjacent to the door opening.

The numeral 6 indicates a yoke-like hand piece applied to the outer plate of the door. 55

The draft device, in its preferred form, is made up of a neck portion 7 and a twyer head 8. In cross section, the neck portion 7 is oblong, and at its outer end it is bolted to the outer plate of the door 1 and registers with an inlet port 9 formed therein. The twyer head 8 is bolted to the inner end of the neck 7 and has a port 10 that registers therewith. In cross section, the twyer head 8 is cylindrical, and for convenience in construction and in 60 the assembling of the parts it is made up of two sections having abutting flanges 8^a that are bolted or otherwise rigidly secured together. The ends of the cylindrical head 8 are closed, but the innermost semi-cylindrical 65 section of the said head is provided with a multiplicity of perforations or air passages 11.

Within the cylindrical head 8 is a semi-cylindrical deflecting plate 12 that extends from end to end of the said cylindrical head 70 and is secured at its ends to the end walls thereof. This deflecting plate 12 is set concentric to and radially co-extensive with the outermost semi-cylindrical section of the said head 8. When the door is closed, the twyer 75 head 8 is projected into the furnace and over a portion of the burning fuel which is contained within the fire box, and in designating directions, as inward and outward, outward is always taken to mean in a direction toward 80 the door opening.

The numeral 13 indicates a damper or valve which is pivotally attached at 14 to the outer face of the door 1, and is adapted to be moved into position to close or to open to any 85 desired extent the air inlet port 9 of the said door.

The operating of the device described, is substantially as follows: The air which will be drawn into the fire box through the port 9 and neck 7, upon entering the twyer head 8, will strike the semi-cylindrical deflecting plate 12 and will be deflected into two currents which, traveling circular courses within the twyer head will again unite with force in 95 the space between the perforated inner head section and the concave side of the deflecting plate 12 and will be expelled with great force 100 through the air passages 11 into the furnace, where the air in a multiplicity of fine streams 105 will be commingled and thoroughly mixed

with the burning products of combustion, thereby very greatly intensifying the combustion and rendering the same complete. As is well known, complete combustion results in a great saving in fuel and with little or no smoke. In actual practice, this improved draft device has been found highly efficient for the purposes had in view.

The twyer head is of considerable length, and is projected a considerable distance through the door opening and into the fire box, so that if applied to an ordinary hinged door, it would, in many instances, not find sufficient clearance in the door opening to permit the door to be swung to and from an open position. The manner of mounting, illustrated in the drawings and above described, makes it possible to pull the twyer head approximately on a straight line outward through the door opening.

What I claim is:—

1. The combination with a furnace door, of a transversely elongated neck portion secured to said door and receiving air from the exterior thereof, a cylindrical head applied to the inner end of said neck and receiving air therefrom, said head having perforations in its most inwardly projecting portion, and an approximately semi-cylindrical deflector located within said head and extending from end to end thereof, with its convex portion alined with said neck and with its concave

surface facing the perforations of said head, substantially as described.

2. The combination with a furnace door having a port, of a neck portion secured to said door and connected to said port, a cylindrical twyer head applied to the inner end of said neck and provided with perforations for the injection of air into the furnace, and an approximately semi-cylindrical deflecting plate concentrically applied within said twyer head and positioned with its convex surface turned toward and alined with said neck portion, substantially as described. 40 45

3. The combination with a furnace door having a port 9, of a neck portion 7 secured to said door and connected to said port, a twyer head 8 secured to the inner end of said neck portion 7 and made up of two approximately 50 55 semi-cylindrical sections, the inner of which sections is provided with perforations 11 for the injection of air into the furnace, and a semi-cylindrical deflecting plate 12 secured within said twyer head concentric to and co-extensive with the outer section of said twyer head, substantially as described.

In testimony whereof I affix my signature in presence of two witnesses.

JOHN C. TELLER.
